UNITED STATES PATENT OFFICE.

HENRY E. HANNA, OF PITTSFIELD, ILLINOIS.

IMPROVEMENT IN PRINTERS' GALLEYS.

Specification forming part of Letters Patent No. **178,924**, dated June 20, 1876; application filed May 22, 1876.

To all whom it may concern:

Be it known that I, HENRY E. HANNA, of Pittsfield, in the county of Pike and State of Illinois, have invented a new and Improved Galley, of which the following is a specification:

In the accompanying drawing, Figure 1 represents a top view of my galley. Fig. 2 is a vertical transverse section of the same on line *x x*, Fig. 1, in position for locking the type; and Fig. 3, an end view of the galley, with locking attachment in folded position.

Similar letters of reference indicate corresponding parts.

The object of my invention is to provide for printing-offices an improved galley, by which the type may be locked in an instant without side-sticks, quoins, and chase, for taking proofs, and unlocked for making corrections without scaling off type.

The invention consists of an adjustable cross bar that is applied by hinged or buckle joints to the side of the galley, to be readily folded out of the way or locked to the type.

In the drawing, A represents a galley of the usual construction; B, a hinged or knuckle-jointed frame that is hinged to and adjusted by slotted plates and set-screws C at the side of the galley. The locking brass bar D extends along side of types, and bears firmly against them when the hinged or knuckle-frame B is completely opened. The locking-bar D may also be adjusted to greater or less distance from the galley by means of slots and clamp-screws of the hinged frame B, as shown in dotted lines in Fig. 1, so as to set it to different width of type, and make it available for any galley in use. The hinged

frame B is provided with suitable handles by which the frame B is raised to be folded up, bringing thereby the locking-bar parallel to and along side of the galley to be entirely out of the way while being instantly ready for use.

When the locking-rod is placed sidewise it leaves the galley clear for the composing-stick, and does not hinder the compositor in his work.

When it is desired to lock the type for taking proof, the locking-bar is brought against the types, and the knuckle or hinged frame lowered and extended to its full width, giving thereby a firm and complete locking of the type at a saving of time and labor, as well in the locking as in the unlocking of the types. As, in the lifting of the hinged frame, the lower part of the locking-bar is first withdrawn from the bottom of the types, while the bar still holds the upper part of the type, the locking-bar may be easily released without producing any scaling off of types, which forms an objectionable feature of the locking attachment of galleys heretofore in use.

Having thus described my invention, what I claim as new, and desire to secure by Letters Patent, is—

The combination, with a printer's galley, of an adjustable locking-bar, applied by a hinge or knuckle jointed frame to be folded out of the way or opened to lock the type, substantially as and for the purpose described.

HENRY EDWIN HANNA.
